A detailed line drawing of a two-story house with a prominent chimney on the left side. A sign is mounted above the front door, featuring a stylized 'J' logo and the word 'INVENTOR' in capital letters. Below the logo, the name 'John Soutar' is written in a large, flowing script. Underneath 'John Soutar', the word 'BY' is printed in a smaller, bold, sans-serif font. Below 'BY', the name 'Robert A. Shields' is written in a cursive script. At the bottom of the drawing, the word 'ATTORNEY' is printed in a bold, sans-serif font. The entire drawing is enclosed within a thin black border.

SELF-CLEARING BLANKING DIES

John Soutar, Huntington, W. Va., assignor to
American Car and Foundry Company, New
York, N. Y., a corporation of New Jersey

Application March 28, 1946, Serial No. 657,757

4 Claims. (Cl. 164—29)

1

This invention relates in general to dies and in particular to dies for cutting or blanking material.

It is generally the practice in blanking dies to use some type of strippers to clear the cut material from the dies for use elsewhere and to permit introduction of uncut material. These strippers are frequently hydraulically operated or resiliently operated by means of springs, rubber blocks, etc. The use of stripping devices to clear the blank from the dies frequently causes distortion of the blanked material, particularly where it is hot or very thin. The cut blanks, due to the taper of the cut edge of material, will of necessity become quite tightly engaged in the dies and resist efforts to remove them. It is an object, therefore, of the present invention to provide blanking dies in which the side edges of the cut blank are automatically released upon raising of the die holder.

A further object of the invention is the provision of a blanking die having floating or movable shear blades carried by the female head.

A still further object of the invention is the provision of a self-clearing blanking die having the parts so arranged as to eliminate the necessity of resilient or power-actuated strippers.

These and other objects of the invention will be apparent to persons skilled in the art from a study of the following description and accompanying drawings, in which:

Fig. 1 is an elevational view of the improved blanking die pair;

Fig. 2 is a plan view of the female die head which in this case is arranged to blank a door sheet for a railway hopper car;

Fig. 3 is a plan view of the male die head;

Fig. 4 is a sectional view taken substantially on line 4—4 of Fig. 1, but showing the dies in closed position;

Fig. 5 is an enlarged sectional view taken substantially on line 5—5 of Fig. 2;

Fig. 6 is a sectional view similar to Fig. 5 but showing the die pairs closed as in Fig. 4, and

Fig. 7 is a cross-sectional view similar to Fig. 4 but showing a slight modification thereof.

Referring now to the drawings in detail, it will be seen that the die pair consists of a bottom carrier A and a top carrier B. Either the top or bottom member may be movable, that is, the top member B may move downwardly toward a stationary lower member or the lower member A may rise upwardly toward the relative stationary member B. In the present instance the bottom member A has bolted or otherwise secured there-

to the male die member made up of a central portion 2 surrounded on three sides at least by straight hardened cutting elements 4, 6 and 8 and by corner pieces 10, 101, 102 and 103 also hardened and occupying the spaces between the straight cutting elements. These cutting elements are fixed with respect to the carrier base A. Since the die has been arranged for blanking sheets for railway car doors punch openings 12 are attached to the bottom member, but it is understood that these may be used or not, dependent upon the type of door to be formed.

The top die carrier B is provided with a central area 18 surrounded by flanges which are machined to provide a substantially horizontal seating surface 20 and a tapered surface 22 arranged at an angle to the flat surface 20. Substantially straight cutting members 24, 26 and 28 are mounted on the upper or female head member B and are adapted to cooperate with male cutting surfaces 4, 6 and 8 respectively. Each of these substantially straight cutting members is provided with a flat surface 30 adapted, when in fully seated position, to cooperate with flat surface 20 and they are also provided with a tapered surface 32 adapted to cooperate with the similarly tapered surface 22 of the carrier B. In order to retain the substantially straight cutters 24, 26 and 28 in position substantially horizontal bolts 34 extend through the cutters and through the flanges of the head member B. These bolts engage vertically elongated slots 36 in the cutting members 24 and are of sufficient length to permit the movable or floating cutters to move vertically from their lowered position to the position in which flat surfaces 30 and 20 engage.

Curved corner pieces 40, 401, 402 and 403 are adapted to cooperate with the curved corner pieces 10, 101, 102 and 103, respectively of the male member and each of these curved corner pieces is provided with a flat upper surface 42 adapted to engage a flat surface 44 of the upper die holder B. Each of the corner pieces is also provided with a tapered surface 46 adapted to engage a similarly tapered surface on the holder B. These corner pieces, due mainly to their lesser thickness, are carried on the upper member B by means of vertically extending bolts 50. These bolts extend through the upper holder with considerable clearance as clearly shown in Fig. 5 and pass with considerable side clearance through elongated slots 52 in the curved members 40, 401, 402 and 403, thus the curved members 40, 401, 402 and 403 are retained against loss and 55 can move laterally with respect to the flanges

of the upper or female die carrier. The tapered surfaces 46 of each of the corner pieces which are associated with the several tapered surfaces of the holder B essentially do not simultaneously function to move the piece into shearing position. Any one or two of the tapered surfaces may function, and the relative movement is permitted due to the large clearance between the bolts 50 and the die corner pieces, it being obvious from the drawings that the guide slots 52 are sufficiently wide to permit this operation. It will also be clear to one skilled in the art that the three tapered surfaces associated with each corner block 40, 401 and 402 are primarily backing surfaces and such being the case, these surfaces may not all be engaged with the corner blocks during its lateral displacement. In addition to the bolts 50 support members 54 may be bolted or otherwise secured to the upper carrier B. Each of the cutting members 24, 26, 28, 40, 401, 402 and 403 is sloped as at 60 and clearly indicated by Fig. 1, thereby reducing the power requirements necessary to cut the sheet material.

When in operation with the die carriers separated a sheet of material S may be slid in on top of the male die head and supported thereby as shown in Fig. 1. Relative movement of the holders A and B toward each other will cause the cutting members 24, 26, 28, 40, 401, 402 and 403 to contact the plate S. This contact will cause the cutters to move inwardly due to the tapers 32 and 46 until the flat surfaces of the cutters engage the corresponding flat surfaces of the holder B. Their further movement will thus be stopped and the cutting action will commence and progress until the plate has been completely sheared and the parts are in the position as shown in Figs. 4 and 6. Separation of the holders A and B will cause the floating or sliding female die members to move downwardly and outwardly, thus freeing the blank and permitting it to either remain or drop onto the top surface of the male die member, from which it may be readily and easily removed.

In some cases where deformation of the blank is harmful the flat surfaces 20 and 44 may be made coextensive with the flat surface 18 of the holder B as shown in Fig. 7 and in this case the entire die holder may be used to straighten the blank following the cutting action. Lifting of the die holder will again release the blank without any possibility of distortion, all as clearly described in connection with Figs. 1 to 6 and since the parts are substantially identical the same reference numerals have been applied.

It will be obvious from the preceding description that during movement of the die holders toward each other the female cutting members will slide inwardly to their final seated position, after which the cutting will take place. Separation of the die holders after cutting will permit the sliding or floating female die members to move outwardly away from the cut blank permitting it to drop by gravity onto the upper surface of the male member. Wherever straightening is desired the die parts can be rearranged slightly as shown in Fig. 7. While the invention has been described more or less in detail with particular reference to the accompanying drawings, it will be obvious to persons skilled in the art that modifications and rearrangements of parts may be made without departing from the scope of the invention as defined by the appended claims.

What is claimed is:

1. A pair of relatively movable shearing die members comprising a male die member and a female die member, movable shear blades carried by said female die member and movable therewith and also relative thereto, inclined surfaces formed on said movable shear blades and female die member and at an acute angle to the direction of movement of the die members, said movable shear blades moving into shearing position substantially at right angles to the direction of shear during movement of the die members toward each other.

2. A pair of relatively movable shearing die members comprising a male die member and a female die member, movable shear blades carried by said female die member and movable therewith and also relative thereto, inclined surfaces formed on said movable shear blades and female die member and at an acute angle to the direction of movement of the die members, said movable shear blades moving into shearing position substantially at right angles to the direction of shear during movement of the die members toward each other and receding from shearing position during separation of the die members whereby the sheared article will be released.

3. A pair of relatively movable die members comprising a male body member and a female body member, one of the body members forming a support for a plurality of fixed relatively straight hardened cutting elements, said supporting body member being formed with recesses intermediate the adjacent ends of the fixed cutting elements, said recesses being defined in part by outer inclined surfaces extending at an acute angle to the direction of movement of the supporting die member and by a base portion, corner die members for seating in said recesses having hardened cutting areas, said corner die members being formed with a lateral side face having acute angle portions corresponding to the acute faces of the recesses and adapted to be normally associated therewith, pins projecting from the base portion of said recesses, slots formed in the corner pieces for receiving said pins, said slots being of a width greater than the diameter of said pins to permit freedom of movement of said corner pieces toward their seating position and lateral movement in accordance with the pitch of the associated coacting angular faces, whereby said corner pieces may move inward laterally during movement to cutting position and laterally outward during movement away from cutting position.

4. The structure of claim 3 characterized in that depressions are formed in the outer faces of the corner pieces about the slots for seating head portions formed in the outer ends of the pins.

JOHN SOUTAR.
